UNITED STATES PATENT OFFICE.

JULES F. BOURLON, OF EVERETT, MASSACHUSETTS.

ROTARY INTERNAL-COMBUSTION ENGINE.

1,023,195.

Specification of Letters Patent. Patented Apr. 16, 1912.

Application filed January 19, 1911. Serial No. 603,463.

To all whom it may concern:

Be it known that I, JULES F. BOURLON, of Everett, in the county of Middlesex and State of Massachusetts, have invented certain new and useful Improvements in Rotary Internal-Combustion Engines, of which the following is a specification.

This invention relates to engines operated by gases under pressure, and more particularly to rotary internal combustion engines.

The object of the invention is to provide an improved rotary internal combustion engine which is simple in construction and efficient in operation.

15 With the above object in view the invention consists in the improved rotary internal combustion engine hereinafter described and particularly defined in the claims.

In the accompanying drawing Figure 1 is 20 a side elevation of one embodiment of the invention, and Fig. 2 is a transverse vertical section of the same.

As illustrated in the drawing, the engine comprises an annular cylinder 1 having two 25 opposed sets of radially disposed arms 2, secured to central bearings 4. The cylinder 1 is provided with a slot 5 in its inner periphery and is mounted upon a base 6 so that the cylinder shall be stationary.

30 Within the annular cylinder 1 are two diametrically opposed pistons 8 and 9, each connected by a radial arm 10, to a central hub 12, which is mounted on a shaft 14, the said shaft being journaled to rotate in the 35 bearings 4. The arms 10 extend through the slot 5 and move therein as the pistons are rotated. Although in the present embodiment two pistons are shown, it is to be understood that any desired number of pistons may be employed, it being merely necessary to provide an annulus of sufficient 40 diameter to allow proper control of the pistons and abutments.

The front end of each piston is wedge-shaped and the rear ends of the pistons are formed with flanges 15 and 16 which overlie the slot 5 and close the latter to form a tight bottom for the explosion chambers. The edges of the slot 5 may be grooved to re-

ceive tongues formed on the edges of the flanges and pistons to enable tighter joints to be formed between the flanges and the cylinder.

The combustible may be compressed by any suitable compressor and delivered through pipes 17, 18, 19 and 20 to the interior of the cylinder 1, said pipes being provided with any approved controlling means for regulating the supply of combustible therethrough. Spark plugs 22, 23, 24 and 25 are provided by means of which the charges are exploded. The products of combustion are exhausted through pipes 26, 27, 28 and 29. There are four sets of these adjuncts in the present instance but their number may be increased as desired.

Four radially movable abutments 30, 31, 32 and 33 are slidably mounted in casings 34, 35, 36 and 37 respectively which project radially outward from the cylinder 1. Four levers 40, 41, 42 and 43 are fulcrumed in pedestals 44 located one fourth of a circumference apart. These levers are provided with elongated slots 45 at their ends, and the stem of each abutment is pivotally connected to the adjacent ends of contiguous levers. The construction is such that when the front or wedge-shaped end of a piston engages the inner edge of an abutment, the latter is forced outwardly, and the next preceding and following abutments are moved inwardly. Thus, when the front end of the piston 8 engages the abutment 30, the latter is forced outwardly and the abutments 31 and 33, attached to the levers 40 and 42, are moved inwardly against the flanges 15 and 16, respectively, thus closing the cylinder behind each piston and forming walls of explosion chambers 46 and 48. At this time the explosive charges are forced through the pipes 17 and 19 into the explosion chambers 46 and 48, respectively, and exploded by the spark plugs 22 and 24, the exhaust ports being closed by the bodies of the pistons. Thus it will be noted that the abutments 31 and 33 move inward simultaneously and charges are exploded simultaneously behind the pistons. As soon as the exhaust ports

26 and 28 are uncovered by the pistons, the products of combustion are discharged through these ports. When the rear edges of the flanges 15 and 16 pass the abutments 33 and 31 respectively, the slot 5 is uncovered and the cylinder is open to the atmosphere to allow a thorough scavenging.

When the piston 8 reaches the abutment 31 the latter is forced outwardly and the 10 abutments 30 and 32 are moved inwardly and then a charge is admitted behind the pistons 8 and 9 through the pipes 18 and 20 to the explosion chambers 47 and 49 respectively and exploded by the plugs 23 and 25 15 respectively. This sequence of operations continues around the cycle, taking place with both pistons simultaneously four times during each revolution of the shaft 14.

Although the invention is shown and described with the pistons rotatable and the cylinder stationary, it is within the purview of my invention to have the pistons stationary, and have the cylinder arranged to revolve.

25 While I have illustrated and described a precise embodiment of the invention, I am aware that many modifications can be made therein by any person skilled in the art without departing from the scope of the invention as expressed in the claims. Therefore, I do not wish to be limited to all the details of construction shown and described, but

What I claim is:

35 1. A rotary internal combustion engine comprising an annular cylinder, a plurality of pistons operating therein, radially movable abutments, and means whereby when an abutment in advance of a piston is moved 40 outwardly the abutment to the rear of the piston is moved inwardly.

2. A rotary internal combustion engine comprising an annular cylinder, a plurality of pistons operating therein, a plurality of 45 levers pivotally mounted on said cylinder, and a plurality of radially movable abutments each pivotally connected to the adjacent ends of contiguous levers.

3. A rotary internal combustion engine 50 comprising an annular cylinder provided with a continuous slot in its inner periphery, a piston in said cylinder having a flange overlying said slot, a plurality of abutments adapted to coact with said flange to form an 55 explosion chamber, and connections whereby when an abutment in advance of the piston is moved outwardly the abutment to the rear of the piston is moved inwardly.

4. A rotary internal combustion engine 60 comprising an annular cylinder provided with a continuous slot on its inner periphery, a piston in said cylinder having a flange for overlying said slot, a plurality of 65 radially movable abutments each adapted to

coact with said flange, and means coöperating 65 with said abutments whereby when the abutment in advance of the piston is moved radially outward, the abutment at the rear of the piston is simultaneously moved radially inward.

5. A rotary internal combustion engine comprising an annular cylinder provided with radially disposed arms, bearings secured to said arms, a plurality of pistons in said cylinder having radially disposed arms 75 connected to a center boss, a shaft journaled in said bearings and carrying said boss, a plurality of radially movable abutments, and means operatively connecting said abutments whereby when the abutment in advance of a piston is moved radially outward, the abutment at the rear of the piston is simultaneously moved radially inward.

6. A rotary internal combustion engine comprising an annular cylinder having a 85 slot on its interior periphery, a shaft, a plurality of pistons in said cylinder, radial arms connecting the pistons to the shaft and passing through said slot, a flange on each piston fitting said slot, a plurality of abutments, and means coöperating with said abutments, whereby when the abutment in advance of a piston is moved outwardly the abutment at the rear of the piston is moved 90 inwardly to coöperate with the flange of the 95 piston.

7. A rotary internal combustion engine comprising an annular cylinder, a plurality of pistons in said cylinder, a plurality of movable abutments, operative connections 100 between the abutments, means for supplying explosive charges to the cylinder, and means for exploding the charges simultaneously behind each of the pistons.

8. A rotary internal combustion engine 105 comprising an annular cylinder, a plurality of pistons in said cylinder, a plurality of sets of diametrically opposed abutments, operative connections between the abutments whereby when one abutment is moved outwardly the preceding and the following abutments are moved inwardly to form the rear walls of explosion chambers, and means for exploding the charges.

9. A rotary internal combustion engine, 115 comprising an annular cylinder, a piston operating therein, radially movable abutments operated by said piston, operative connections between the abutments whereby when an abutment in advance of a piston is moved 120 outwardly the abutment to the rear of the piston is moved inwardly, and means for supplying explosive charges to the cylinder.

10. A rotary internal combustion engine, 125 comprising an annular cylinder, a piston operating therein, a series of abutments moved outwardly by the piston, and operative connections between the abutments, whereby

when an abutment in advance of the piston is moved outwardly the abutment to the rear of the piston is moved inwardly.

11. A rotary internal combustion engine comprising a cylinder, a plurality of pistons in said cylinder, a plurality of abutments moved outwardly by said pistons, and operative connections between the abutments whereby when the abutment in advance of a

piston is moved outwardly the abutment at 10 the rear of the piston is moved inwardly.

In testimony whereof I have affixed my signature, in the presence of two witnesses.

JULES F. BOURLON.
